UNITED STATES PATENT OFFICE.

EVERT M. THOMPSON, OF EVANSVILLE, INDIANA.

BERRY-BOX.

SPECIFICATION forming part of Letters Patent No. 361,557, dated April 19, 1887.

Application filed January 29, 1887. Serial No. 225,945. (No model.)

To all whom it may concern:

Be it known that I, EVERET M. THOMPSON, of Evansville, county of Vanderburg and State of Indiana, have invented certain new and 5 useful Improvements in Berry-Boxes; and I do hereby declare that the following is a full, clear, and exact description thereof, reference being had to the accompanying drawings, in which like letters refer to like parts.

10 My invention relates to the construction of small boxes from blanks of thin wood, and intended to hold berries for shipment, and will be understood from the following description.

15 In the drawings, Figure 1 represents a perspective view of the box made up. Fig. 2 is a top view of the two blanks crossing one another, the scores in which the blanks are to be bent up indicated by the dotted lines.

20 Each box is made of two blanks which are shaped alike, and one is laid across and at right angles to the other, making the bottom of the box double, as indicated in Fig. 2. Each blank has tabs or splints *t t'* at each end, preferably two, with an opening between them to 25 allow ventilation of the berries, and substantially in line with the bottom of this opening each blank is scored transversely across its width to allow the splint ends to be bent up along the scores in shaping the box. The 30 splint ends of the blank are bent up at right angles to the bottom, and one blank thus bent up is set across at right angles to the other, so that the splints of one blank form two sides, and the splints of the other blank form the two 35 other sides of the box. An outside binding-hoop, *h*, or an inside hoop, *h'*, or both, are then set in the position shown in Fig. 1, and nailed through the splints with small nails, supporting the box at all points and holding 40 it in proper position, no other means being used to fasten the blanks together. A box made in this way is substantially square on the bottom and a little less in height than the dimensions of the bottom.

45 It will be seen that the ends of the tabs or splints project above the hoop *h* some distance, and this peculiar construction is the essential feature of my invention. These boxes are intended to hold berries, and are necessarily 50 small, the custom of the trade generally de-

manding that they shall hold a quart, especially as regards strawberries.

These boxes when first filled must be heaped up, so that when the berries have settled from the jostle of transportation the box will at 55 least be level full. Again, these small baskets or boxes must of necessity be packed in large boxes called "crates," which usually contain about sixteen of the one-quart baskets, and in filling this crate it becomes necessary to place 60 the small baskets in tiers one above another in order to make a compact square-shaped crate.

In ordinary baskets, after they are filled level full at first, they settle during transportation, so that when they reach the retailer the boxes 65 do not appear to be full, and are unsalable. Again, if they are filled heaping full when put into the crate, being in tiers one above another, such packing mashes the berries. In order to avoid the difficulties and objections 70 just mentioned, I have devised the basket herein shown, whose splints or tabs project above the binding-hoops in the manner shown. Now, in these baskets the berries may be heaped up and the package appear very full, 75 and yet the contents are protected from injury in transportation. After my baskets are placed in tiers in the shipping-crate and are full of berries, the upper ends of the splints will still be above the berries, and in packing them in 80 crates, after putting one layer of these boxes in place, a thin sheet of wood is placed on top, and is supported by and rests upon the projecting ends of these splints, and this thin sheet of wood answers as a floor upon which 85 to set the next tier of baskets, and in this manner I can fill the crate with any number of baskets without injury to the berries. Again, this peculiar construction of the box with the projecting splints provides ample ventilation 90 for the berries between the layers of wood, a thing greatly to be desired in the transportation of small fruits.

I am aware that berry-boxes have been made of blanks of thin wood having openings in 95 the sides for ventilation, and having a single pair of splints projecting above the sides to support the cover, and I do not, broadly, claim the same as my invention; but none of these have been formed of splints crossing each 100

other at right angles, and the ends of the splints projecting on sides and ends above the points where they are secured together in the manner herein shown.

5 What I claim, and desire to secure by Letters Patent, is the following:

1. A berry - box formed of two or more blanks laid crosswise, scored across, and bent up in the scores, secured in position by inner and outer binding - hoops, the ends of the splints projecting above the hoops as a support for the cover, substantially as shown and described.

2. A berry-box formed of two blanks laid crosswise, their ends cut out to form tabs with 15 openings between them, scored across their width, and bent up in the scores, secured in position by one or more binding-hoops, the ends of the tabs projecting above such hoops, substantially as shown and described.

Signed by me January 22, 1887.

EVERT M. THOMPSON.
